(57) **CLAIM**

The ornamental design for an electronic product protective case, as shown and described.

DESCRIPTION

FIG. 1 is a front view of an electronic product protective case of the present invention when the case is in a closed configuration.

FIG. 2 is a back view of the electronic product protective case shown in FIG. 1.

FIG. 3 is a left view of the electronic product protective case shown in FIG. 1.

FIG. 4 is a right view of the electronic product protective case shown in FIG. 1.

FIG. 5 is a top view of the electronic product protective case shown in FIG. 1.

FIG. 6 is a bottom view of the electronic product protective case shown in FIG. 1.

FIG. 7 is a view of the interior of the electronic product protective case of the present invention when the case is in an open, fully expanded configuration.

FIG. 8 is a perspective view of the electronic product protective case of the present invention when the case is in a deployed, self-standing configuration for supporting an electronic product to be viewed at a tilted angle.

FIG. 9 is another perspective view of the electronic product protective case of the present invention as shown in FIG. 8.

FIG. 10 is a front view of the electronic product protective case as shown in FIG. 8.

FIG. 11 is a back view of the electronic product protective case as shown in FIG. 8.

FIG. 12 is a left view of the electronic product protective case as shown in FIG. 8.

FIG. 13 is a right view of the electronic product protective case as shown in FIG. 8.

FIG. 14 is a top view of the electronic product protective case as shown in FIG. 8; and,

FIG. 15 is a bottom view of the electronic product protective case as shown in FIG. 8.

The broken lines represent portions of the structure of the electronic product protective case that form no part of the claimed design.

1 Claim, 13 Drawing Sheets
